UNITED STATES PATENT OFFICE.

JOHN C. BAUMGARTEN, OF PORTLAND, OREGON.

BOTTLE OPENER.

Application filed April 28, 1924. Serial No. 709,500.

To all whom it may concern:

Be it known that I, JOHN C. BAUMGARTEN, a citizen of the United States, and a resident of Portland, county of Multnomah, and State of Oregon, have invented a new and useful Improvement in Bottle Openers, of which the following is a specification.

My invention relates to bottle de-capping implements.

10 Since bottles containing soda water, and the like, are generally closed by crimped on caps, a special implement must be used for removing these caps. There are two types of these implements generally used. One of 15 these is a device which is applied by hand. Since this device is readily laid down in one place when required in another, it is not always handy during the rush of customers. The other type is a device located at some 20 station to which the bottle must be taken, and hence unless several of this type of device be installed it would necessitate considerable running back and forth.

25 So the object of my invention is to provide a simple, inexpensive implement for prying off said caps, and to construct such implement in the form of a ring which may be carried about on the finger, thus be handy for instant use.

30 A further object of my invention is so to construct my implement that it will not impose undue strain on, or tend to bruise the finger in removing said caps.

35 I attain the above desired objects of my invention by an implement in the form of a circular band, preferably of substantial width, and substantially rhombiform so as to locate an edge of one side of the band in the crease occurring at the juncture of the 40 finger with the hand and locate the opposite edge of the same side so as to bear against the knuckle formed by said joint. I also round these edges of the band which come in contact with the finger; in other words have 45 no sharp edges. Furthermore, a marker may be provided on the outer face of said band as, for instance, a pencil point projecting perpendicularly therefrom.

50 The above described features and others incidental thereto are hereinafter fully described with reference to the accompanying drawings, in which:

55 Fig. 1 is a large scaled perspective view of my bottle de-capping device in position during the lifting of a cap from the mouth of a bottle and shows in dotted outlines the

relative position of the hand as the cap is lifted from the bottle;

Fig. 2 is a perspective view of a ring in position on the operator's finger showing the 60 palm of the hand;

Fig. 3 is a perspective view of the hand showing the ring in position for lifting the cap from the bottle, and shows the operator's 65 hand from one side;

Fig. 4 is a fragmentary perspective view of the ring and the back of the operator's hand;

Fig. 5 is a side elevation of a modified 70 type of device;

Fig. 6 is a front elevation of the same;

Fig. 7 is a still further modification of my invention; and

Fig. 8 is a front elevation of the same.

My improved bottle opener is made in the 75 form of a ring *a* which is adapted to fit snugly over the finger of the wearer and which is provided with an elongated slot *b* which is substantially parallel with the edges of the ring and thus extends circumferentially of the ring. The lower edge of 80 this slot *c* is curved and is preferably undercut as shown in Figs. 1 and 3. The upper edge *d* of the slot is preferably provided with a sharp projection *d'* which is adapted 85 to perforate the cap when the device is being used to lift the same. This projection, however, is not necessary to lift the cap but is used merely to perforate the cap and to permit any difference of pressure 90 within the cap and the atmosphere to become equalized so as to expedite the removal of the cap. Except for the projection *d'*, the upper edge *d* of the slot is relatively 95 straight so as to provide a shoulder of substantial length about which the ring can 100 fulcrum as it lifts the cap from its position on the mouth of the bottle. The ends *e* and *f* of the ring preferably make an oblique angle with the periphery and the upper end surface *f* is preferably slightly curved so as to conform to the shape of the finger. When the edges *e* and *f* of the ring 105 make an oblique angle with the periphery, it permits the portion *a'* of the ring *a* which fits over the back of the hand, to extend rearwardly a sufficient distance so that it overlies the knuckles at the base of the finger on which the ring is worn which 110 is thus enabled to exert substantially all of the pressure necessary to tip the ring about its fulcrum on the top of the cap.

The opposite side also thus fits about the finger so that its edge is arranged to lie along the crease at the juncture of the finger with the hand. This particular construction provides a bearing portion on the outer side of the ring, that is, at the knuckle of the wearer's hand, which outer bearing portion is in rear of the bearing portion on the inner side of the ring, that is, at the juncture of the finger with the palm. The portion a' on the back of the ring a is also preferably provided with a piece of writing lead g so that the decapping device may serve not only as a cap remover but also as a marker by the use of which, the operator may note the amount of the service on the check.

As shown in Figs. 5 and 6, it is not absolutely necessary that the under surface of the recess be curved and under cut, because a sufficient grip may be had by providing a ring shaped opener a^2 , the lower surface c' of which is preferably flat but in this ring also the periphery of the ring and the ends make oblique angles with each other and thus the surface c' makes a similar angle with the periphery.

In Figs. 7 and 8 I show how the ring a^3 may be made to resemble an ordinary finger ring and shows how the recess b' may be formed with a curved upper portion d^2 and a similar curved lower portion e^2 . The two curved portions co-operate to lift the cap from off the mouth of the bottle which I have lettered h .

As shown in Figs. 1 and 3, the portions of the ring that grip the bottle cap, are arranged substantially parallel to the edges of the ring and transversely of the finger. In use, therefore, the cap is removed by placing the gripping portions over the cap to remove the same and then gripping the bottle tightly rather than by using the finger as a pry as would be the case where the gripping means extends normal to the edges. This, together with the making of the ring substantially rhombiform, serves to decrease the pressure and bruising effect of the ring on the back of the finger, and permits its use for long periods without injury or pain to the wearer.

I claim:

1. A bottle opener in ring form to be worn upon the finger and having a comparatively broad peripheral surface, the rear edge of such surface having a bearing por-

tion on the outer side of the ring as worn in rear of the bearing portion at the inner side of the ring as worn, the inner peripheral surface of the ring being formed with an opening having its rear edge formed to present a lip disposed wholly in the plane of such peripheral edge.

2. A bottle opener in ring form to be worn upon the finger and having a comparatively broad peripheral surface, the rear edge of such surface having a bearing portion on the outer side of the ring as worn in rear of the bearing portion at the inner side of the ring as worn, the inner peripheral surface of the ring being formed with an opening having its rear edge formed to present a lip disposed wholly in the plane of such peripheral edge, the free edge of the lip being of wedge form.

3. A bottle opener in ring form to be worn upon the finger and having a comparatively broad peripheral surface, the rear edge of such surface having a bearing portion on the outer side of the ring as worn in rear of the bearing portion at the inner side of the ring as worn, the inner peripheral surface of the ring being formed with an opening having its front and rear edges spaced apart a distance exceeding the depth of the cap rim, with the lower of such edges formed to engage beneath such rim.

4. A bottle opener in ring form to be worn upon the finger and having a comparatively broad peripheral surface, the rear edge of such surface having a bearing portion on the outer side of the ring as worn in rear of the bearing portion at the inner side of the ring as worn, the inner peripheral surface of the ring being formed with an opening having its front and rear edges spaced apart a distance exceeding the depth of the cap rim, with the lower of such edges formed to engage beneath such rim, the width of the opening in the ring permitting the projection of a portion of the cap rim therein in the operative application of the opener.

5. A bottle decapping tool in ring form, adapted to be worn upon the finger and having a comparatively broad peripheral surface, the ring wall being substantially uniform in thickness and formed with an opening therethrough, with one edge of the opening formed as a cap-engaging lip within the plane of the peripheral surface.

JOHN C. BAUMGARTEN.
